(57) **CLAIM**

The ornamental design for an elongated ice pod, as shown and described.

DESCRIPTION

FIG. 1 is a perspective side view of the elongated ice pod showing my new design,

FIG. 2 is a first side view of the same showing a short side of the elongated ice pod,

FIG. 3 is a second side view of the same, shown from an opposite side of the elongated ice pod,

FIG. 4 is a third side view showing a long side of the elongated ice pod,

FIG. 5 is a fourth side view showing the opposite long side of the elongated ice pod,

FIG. 6 is a top view of the same; and,

FIG. 7 is a bottom view of the same.

The broken lines in the drawings depict an inlet water valve and an outlet water valve that form no part of the claimed design.
